UNITED STATES PATENT OFFICE

JOHN C. DINSMORE, OF PROVIDENCE, RHODE ISLAND, ASSIGNOR TO HOPE WEBBING COMPANY, OF PAWTUCKET, RHODE ISLAND, A CORPORATION OF RHODE ISLAND

FINISHING WELT

Application filed May 28, 1930. Serial No. 456,497.

This invention relates to finishing welts intended particularly for the upholstery of automobile bodies but useful wherever it is desired to employ a finishing welt or similar strip attached by concealed fastenings.

In one aspect my invention consists in improvements in finishing welts of the type described in U. S. Letters Patent No. 1,226,600. In another aspect, my invention consists broadly in a new article of manufacture, viz., an integrally-fabricated textile or integrally-woven finishing welt. Considering my invention first as being in the nature of an improvement upon such finishing welts as those shown in U. S. Letters Patent above identified and which are fabricated from leather, cloth or other sheet material which must be cut, folded, cemented and stitched, and which thus offer an opportunity for deterioration in respect to their cemented or stitched joints; the welt of my invention provides a continuous integral structure inherently uniform in its dimensions, superior in strength and wearing qualities and not subject to deterioration in the respects noted.

Considering next my invention as being a new article of manufacture comprising an integrally-fabricated finishing welt, numerous important and valuable features will be apparent. In the first place, a welt so constructed offers an inviting opportunity for ornamental finish in that by appropriately varying the character of the warp and weft threads or the pattern of the weave any selected design may be produced in the fabric of the welt. For example, it is contemplated that a series of silk, rayon or worsted threads may be employed to create a decorative effect along the borders or other parts of the welt. Opportunity is also afforded for employing a heavier or less expensive warp thread in the backing of the welt than in the exposed portion thereof and this is advantageous both from the standpoint of economy and in that by this expedient a heavy backing may be provided, affording firm anchorage for the attaching nails without impairing the ornamental appearance of the face of the welt.

In the embodiment of the invention here-

in shown, the welt is formed with a plurality of spaced bead cores which are encased in woven tubes and these tubes are merged into an integrally-woven intermediate connecting portion. It will be apparent that such a welt may be produced to good advantage in a loom where the bead cores may be constituted as warp ends, and as the sheaths or tubes are woven continuously upon the bead cores they conform and fit perfectly thereon, incorporating the cores into the integral structure of the welt. My invention contemplates a welt having cores woven into its structure and as a further preferred feature, the welt of my invention includes an outwardly-extending flange portion which is integrally woven with the core-encasing tubes. The flange portion may be of single or multiple ply and is integral with the backing portion.

These and other features of the invention will be best understood and appreciated from the following description of a preferred embodiment thereof, selected for purposes of illustration and shown in the accompanying drawings, in which

Fig. 1 is a view in cross section of the welt, on an enlarged scale;

Fig. 2 is a fragmentary longitudinal sectional view on the line 2—2 of Fig. 1; and

Fig. 3 is a view in perspective of the welt in substantially its normal size.

Referring first to Fig. 3, it will be seen that the welt selected for illustrating my invention comprises a pair of bead cores 17, each of which is encased in a woven tube 18. Each of the tubes 18 is merged into an outwardly-extending flange portion 22 and these in turn are merged into a backing 24, integrally woven with the flange portions and underlying the same. The welt may be provided with an ornamental stripe 25 at each side of the bead formed by a series of rayon warp threads as will presently be described, and other variations in the materials or weave may be assorted to embellish the appearance of the article. The welt is so woven that the beads normally contact with each other and cover the backing 24. In attaching the welt, the beads are temporarily spread apart and tacks 28 may then be driven through the back-

ing in the manner as illustrated in Fig. 3. When the beads are released, they close together, concealing and protecting the heads of the attaching tacks.

Referring now to Figs. 1 and 2, it should be explained that the warp threads are represented in cross section in Fig. 1 and the weft threads in cross section in Fig. 2. The bead cores 17 are also constituted as warp ends. 10 As herein shown, they are represented as composed of a twisted paper cord, although it is to be understood that any desired material may be employed as best adapted for the particular purpose intended for the welt. For 15 example, a textile cord of twisted, braided or plain strands, a leather, fabric or rubber cord or a wire may be employed.

The warp threads 10 of the sheath or tube 18 are distributed about the periphery of the 20 cores 17 and extend in overlying relationship outwardly from both tubes. The warp threads 12 of the backing portion 24 extend from one margin or selvage of the welt strip to the other. The weft threads 16 extend 25 laterally of the backing and are interwoven with the warp threads 12 in any suitable order or weave. The weft is a continuous thread interlacing successively with the warp threads of the backing, the plies of the flanges 30 and the sheaths encasing the cores in a manner similar to the illustration in Fig. 1, thereby forming an integrally formed textile. It will thus be seen that each tube 18 is interwoven with an outwardly-extending flange 35 portion 22 having two or more plies and that the plies of the flange portion are interwoven with a backing portion 24 which connects the two sides of the welt. In other words, the concatenation of the threads is such as to provide 40 that the sheaths or tubes 18 for the beads are integral with the backing 24 and side strips or flanges 22. The warp threads 12 of the backing may be of heavier and less expensive material than the warp threads 10 of the tubes 18 and flange portions 22 of the 45 welt. To indicate such difference in character, the warp threads 12 are shown in heavier sections than the warp threads 10.

In the illustrated construction, the flange 50 portions 22 of the welt are united to the backing 24 by spaced warp binder threads 14 which, as shown in Fig. 2, are arranged to intermesh with the weft threads 16 in both the backing and in the flange portions. The 55 warp binder threads are shown as spaced from each other by a series of four warp threads, although the number and arrangement of the warp binder threads is of secondary importance and may be selected as desired. In the illustrated welt the four warp 60 threads 13 located between the warp binder threads 14 in the upper ply of the flange portion are preferably of silk or rayon, so that a decorative stripe is formed in the exposed 65 surface of the welt extending parallel with

the edge thereof in spaced relation from the bead. It will be seen that the tube-encased cores are thus connected to the backing 24 adjacent to but inwardly of its edges, this arrangement giving heavier and stronger 70 edge portions to the welt and serving to more substantially secure the tube-encased cores thereto and to hold them firmly in resilient contact with the backing. It will furthermore be understood that each woven tube surrounds its core 17 and has both its sides or ends extending integrally over and secured to an edge portion of the backing in a manner providing multiple ply edges for the welt. 75

I have illustrated and described a preferred 80 construction of woven finishing welt which presents the advantages above discussed and which is suitable for finishing automobile upholstery and for various other purposes. It will be understood, however, that the invention is in no sense limited to the illustrated 85 form of welting nor to the specific design of the weave. Where it may be desired to use the welt under different conditions from those mentioned, its proportions may be correspondingly varied and in some cases a greater 90 number of beads provided on its face.

It will be apparent from the foregoing disclosure that I have produced a finishing welt of a type not heretofore available and which, 95 by reason of its characteristic integrally-woven construction, is more durable and less liable to deterioration than welts fabricated from sheet material by the use of cement, stitching or other means. Its advantages 100 from the standpoint of ornamental appearance have also been touched upon, it being possible to produce many variations of design both in the patterns of the weave and the color and character of the materials employed. It is, moreover, of special commercial value in that it may be conveniently woven of thread matching or blending with the fabric of the upholstery upon which it is 105 displayed.

My invention not only provides a welt of greater uniformity and durability and one more attractive and ornamental in appearance, but in addition supplies a new article 115 of commerce which can be produced mechanically at one operation to greatly economize in its cost of manufacture. While I have described the improved welt as being woven, for example on a narrow ware loom, it is likewise capable of being fabricated as a 120 unitary structure on a braider or other similar machine, it being understood that the textile portion of the welt is formed by intermeshing relatively angular threads, as the warp and weft threads 10 and 16, about the cores 17 and intermeshing threads including certain of the first named threads, as the weft threads 16, in a position laterally of the core or cores to form the backing strip. 125

It is to be understood, therefore, that I do 130

not intend to be limited to the precise form or structure of the welt as herein shown and described, or to the exact method of fabricating the same as disclosed, the improved article being susceptible of various modifications which would fall within the spirit and scope of the invention as expressed in the appended claims.

My invention also includes within its scope 10 a method of weaving the novel welt herein disclosed and which is characterized by the steps of surrounding the bead cores with warp threads, providing a connecting row of warp threads and then weaving weft threads continuously about all the warp threads to 15 form circularly-woven tubes upon the bead cores and a flat connecting portion.

Having thus described my invention, what I claim as new and desire to secure by Letters 20 Patent is:

1. A woven finishing welt for upholstery or the like, comprising a plurality of parallel bead cores encased in seamless woven tubes which are integrally merged into an 25 integrally-woven intermediate connecting portion, the tube-encased cores being connected to said portion adjacent to but inwardly of the edges thereof and being bodily movable away from said portion.

2. A woven finishing welt for upholstery or the like, comprising parallel bead cores each encased in a woven tube, each tube interwoven with a backing integrally woven with both said tubes and woven together in 35 multiple ply at the edges of the welt.

3. A woven finishing welt for upholstery or the like, comprising spaced parallel cord-like cores, and integrally-woven tubes enclosing the cores, each tube being merged into 40 an outwardly-extending flange portion of multiple thickness which portions integrally merge into a common intermediate connecting portion of less thickness.

4. A woven finishing welt for upholstery, 45 comprising spaced parallel longitudinally-disposed cores, and integrally-woven tubes enclosing the cores, each tube merging integrally into an outwardly-extending flange portion having warp threads of the same color 50 or as the warp threads of the tubes, and also merging into an intermediate connecting portion having warp threads of a different color from those of the tubes, an intermediate base portion integrally connecting the flange portions of the two tubes, and warp threads integrally connecting the flange and base portions.

5. A woven finishing welt for upholstery, 60 comprising a single ply backing woven to extend upwardly and inwardly at its edge, the inwardly-extending portion being merged into the circumference of a circularly-woven tube and thence extending outwardly between the backing and the inwardly-extending portion of its edge, and warp binder 65

threads uniting the backing with the overlying plies thus formed.

6. A woven finishing welt for upholstery, 70 comprising parallel woven tubes each merging into an outwardly-extending flange portion, and a backing underlying said flange portions, being integrally woven therewith at its outer edges and locked thereto by spaced warp binder threads.

7. A woven finishing welt for upholstery, 75 comprising parallel woven tubes each being merged into a multiple ply outwardly-extending flange portion, warp binder threads connecting the plies of said flange portion, and a backing integrally woven with said flange portions and underlying the same.

8. A woven finishing welt for upholstery, 80 comprising parallel circularly-woven tubes each integrally woven with a laterally-extending flange portion, said flange portions 85 being merged into an underlying backing, and spaced warp binder threads arranged to engage weft threads in the backing and in said flange portion.

9. A woven finishing welt for upholstery, 90 comprising circularly-woven tubes of substantially equal size each integrally woven with a multiple ply laterally-extending flange portion, said flange portions being merged into an underlying backing, spaced warp 95 binder threads uniting the flange and backing, and warp threads between said binder threads of a character different from those located outside the binder threads.

10. A woven finishing welt for upholstery, 100 comprising circularly-woven tubes of substantially equal size each integrally woven at both sides with a multiple ply laterally-extending flange portion which at its outer edge is turned under and merged into a backing woven integrally therewith, and a binder thread spaced from the edge of each flange portion and serving to unite the backing thereto.

11. The method of weaving beaded finishing welts, which consists in arranging a pair of bead cores as warp ends, surrounding the bead cores with spaced warp threads, arranging an intermediate row of warp threads, and then weaving weft threads continuously 110 and progressively about all of said warp threads forming circularly-woven tubes about the bead cores integrally merging into a connecting web of multiple ply thickness at its edge portions.

12. The method of weaving beaded finishing welts, which consists in arranging bead cores as warp ends, surrounding the bead cores with parallel warp threads, providing an intermediate row of warp threads extending beyond the line of the bead cores and a second tier of warp threads superimposed above the threads at the edges of said row, weaving weft threads about said warp threads, and simultaneously manipulating 125 130

spaced warp threads to bind oppositely disposed portions of the weft threads together.

13. A woven finishing welt for upholstery or the like, comprising a bead core encased in a seamless woven tube both side portions of which merge integrally into a woven base, the tube-encased core normally engaging resiliently against the adjacent portion of the base but being movable away therefrom.

14. The method of producing a textile beaded welt consisting in providing a longitudinal core and intermeshing relatively angular threads thereabout to form a seamless casing over the core and intermeshing threads including certain of the first named threads laterally of the core to form a backing strip so connected to the encased core as to hold the same resiliently in contact with the backing strip but permit lifting it therefrom.

15. The method of producing a textile beaded welt consisting of providing a longitudinal core and intermeshing relatively angular threads thereabout to form a seamless casing over the core and intermeshing threads including certain of the first named threads laterally of the core to form a backing strip connected to the casing at a point adjacent to but inwardly of an edge of the strip and so spaced from the encased core as to permit lifting of the same from the backing strip.

16. The method of producing a textile beaded welt consisting of providing two longitudinal cores and intermeshing relatively angular threads thereabout to form a seamless casing over each core and intermeshing threads including certain of the first named threads laterally of the cores to form a backing strip connected to the casings at points respectively adjacent to but inwardly of the edges of the strip and so spaced from the encased cores as to permit lifting of the same from the backing strip.

17. The method of producing a textile beaded welt consisting of providing two relatively adjacent longitudinal cores and intermeshing relatively angular threads thereabout to form a seamless casing over each core and intermeshing threads including certain of the first named threads laterally of the cores to form a backing strip having its edge portions connected to the casings at points so spaced from the inwardly-extending casings as to permit lifting of the same from engagement with the intermediate portion of the strip.

JOHN C. DINSMORE.
